(57) **CLAIM**

The ornamental design for a tire tread, as shown and
described.

DESCRIPTION

FIG. 1 is a front perspective view of a tire tread showing my
new design, it being understood that the tread pattern repeats
uniformly throughout the outer circumference and shoulder
of the tire, the opposite side perspective view being identical
thereto; and,

FIG. 2 is an enlarged fragmentary front elevation view of the
tire tread thereof of FIG. 1.

The broken lines in the drawing indicate that the configura-
tion of the three circumferential tread grooves forms no
part of the claimed design. In the drawings, the dark stippled
surface shading represents the recessed groove portions of
the tire tread and shoulder areas. The broken line disclosure
of the tire sidewall and inner bead is for illustrative purposes
only and forms no part of the claimed design.
